COMBINED STAPLER AND STAPLE REMOVER OR SIMILAR ARTICLE

Robert H. Crowle, Mount Prospect, William G. Crowle, Deerfield, and Charles E. Jones, Evanston, Ill., assignors to Swingline Inc., Long Island City, N.Y., a corporation of New York

Filed Apr. 4, 1961, Ser. No. 64,605

Term of patent 14 years

(Cl. D74—1)

FIG. 1

FIG. 2

FIG. 3

FIG. 4

FIG. 5

FIG. 1 is a top plan view of a combined stapler and staple remover or similar article, showing our new design.

FIG. 2 is a bottom plan view thereof.

FIG. 3 is a side elevational view, the side opposite thereto being similar in appearance.

FIG. 4 is a front elevational view thereof.

FIG. 5 is a rear elevational view thereof.

We claim:

The ornamental design for a combined stapler and staple remover or similar article, as shown and described.
